UNITED STATES PATENT OFFICE.

JACOB M. LONDON, OF TUNNELTON, PENNSYLVANIA, ASSIGNOR TO SULLIVAN MACHINERY COMPANY, OF CLAREMONT, NEW HAMPSHIRE, A CORPORATION OF MASSACHUSETTS.

MINING MACHINE.

Application filed May 15, 1915, Serial No. 23,449. Renewed March 3, 1924.

This invention relates to mining machines and more particularly, though not exclusively, to coal mining machines employing movable cutting devices adapted to be presented to the coal to cut a kerf or channel therein.

The invention will be best understood by reference to the following description in connection with the accompanying drawings, which description and drawings relate to a preferred construction of one specific embodiment of my invention, while the scope of my invention is more particularly pointed out in the appended claims.

15 Referring to the drawings:

Fig. 1 is a plan of one embodiment of my invention without the separable coal cutter;

20 Fig. 2 is a side elevation thereof also without the separable coal cutter;

Figs. 3, 4, 5 and 6 illustrate a preferred construction of my invention in various positions during operation;

25 Fig. 7 is a vertical section on the line 7—7 of Fig. 1 showing detail of the latch mechanism;

30 Fig. 8 is a vertical section on the line 8—8 of Fig. 2 showing detail of mechanism for positioning the swivelled frame when retracted in the guiding frame;

Fig. 9 is a vertical section on line 9—9 of Fig. 1 showing detail of the clamping mechanism;

35 Fig. 10 is enlarged side elevation of a portion of the truck frame and sliding frame, with a portion broken out to show the rabbeting.

Fig. 11 is a partial vertical section on line 11—11 of Fig. 1 showing the turntable locking mechanism;

40 Fig. 12 is a vertical section of the end of the turntable frame on the line 12—12 of Fig. 1;

45 Fig. 13 is a vertical section on the line 13—13 of Fig. 1;

Fig. 14 is a vertical section on the line 14—14 of Fig. 1;

50 Fig. 15 is a side elevation of one embodiment of my invention including the coal cutter mounted thereon, parts of the truck being broken away and parts of the machine and truck being omitted to facilitate illustration, and

Fig. 16 is a plan view of one embodiment of the apparatus shown in Fig. 1, but with 55 the turntable angularly inclined.

Fig. 17 is a vertical section in the same plane as Fig. 12 showing details of the truck drive.

While this invention is by no means restricted to feeding, guiding and positioning mechanism, it pertains largely thereto and for this reason I have shown my feeding and positioning mechanism, system and connections as used in connection with a preferred type of chain cutter machine heretofore largely used for cutting coal while sliding on the mine bottom and while being fed, guided and positioned by flexible tension members in a manner which may resemble somewhat the mechanism of the patent to Mitchell No. 656,414. The Mitchell type of machine is very useful for room and pillar cutting and in a modified form for long wall cutting, but it has certain disadvantages for entry cutting which it is one of the purposes of this invention to overcome without in any way impairing the value of the machine for other purposes.

In the specific embodiment of my invention illustrated in the drawings, I have shown a chain cutting machine of the before described type comprising the shoe 100, the cutter bar 101, the cutter chain 102, the flexible feeding and positioning means typified by 65 the chain 103 and the source of power illustrated by the motor 104 adapted through any desired power transmission devices to impart cutting movement to the chain 102 and feeding and positioning movement of the 70 chain 103, the feeding mechanism as usual in such machines being adapted when once connected in one relation to draw in one end of the chain at a predetermined slow cutting speed and when once connected in another 75 relation to draw in the other end of the chain at a predetermined higher moving speed. Machines of this type are of great utility in room and pillar cutting and in long wall cutting preferably while sliding along the 80 mine bottom adjacent a wall to be undercut, the machine pulling itself along by tensioning a flexible tension means attached to a fixed position in advance of the machine and being held up to the work by cooperating 85 flexible tension means attached to a fixed

point behind the machine, the advance tension means being preferably operatively connected to the front of the machine at a point relatively close to the face to be cut and the rear tensioning means being operatively attached to the machine at a point at a greater distance from the face to be cut than is the advance tensioning means aforesaid. As heretofore designed, machines of this character have not been adapted for radial cutting. It is among the purposes of this invention to provide improved means for positioning, swinging, guiding and holding mechanism which may be used to adapt said machine to radial cutting especially for entry cutting preferably without in any way impairing its usefulness and adaptability for room and pillar or long wall work.

To accomplish this I may provide any suitable rotatable coal cutter supporting means as the turntable 1 rotatably mounted on the turntable bed 2, provided with the step-bearing 3. It is desirable to provide turntable locking means as the pin 4 adapted to pass through holes 5 in the turntable 1, and holes 6 in the turntable bed 2 to lock them in any desired relative position.

It is advantageous to provide a frame 7 in which said turntable as a whole may be guided and supported for longitudinal sliding movement. An efficient method of accomplishing this is to attach parallel guiding members, typified by the angle irons 8, to the turntable bed 2 which may cooperate with guiding means typified by parallel angle irons 9 on the frame 7 between which the guiding members 8 may slide. To prevent tipping of the turntable I have found it desirable to provide rabbeting between the guiding members, typified by the gib 10, attached to the angle iron 9 and the gib 11 attached to the angle iron 8.

To lock said turntable bed at any desired point in the frame 7, I may provide clamps 12 having set screws 13, and adapted to clamp the guide 8 to the guide 9 and hence prevent relative movement of such guides. To firmly position and secure the coal cutting machine on the turntable, I may provide any suitable positioning means, but I prefer to attach thereto a frame which may consist of parallel angle irons 37 serving to prevent lateral displacement of the coal cutter by engaging the sides of the bed thereof, and a back for the frame which may be typified by the angle iron 52. To firmly secure the coal cutting machine in the frame, preferably with its center of gravity disposed, as shown, substantially over the swivel, in such a manner as to facilitate movement of the parts. I may provide keepers 38 or any other suitable securing means which may be adapted to prevent movement of the machine in the frame.

To promote ease of transportation I pref-

erably provide the frame 7 with a plurality of wheels 14 mounted on axles 15 and 56, the axle 15 turning in journals 16 and provided with a sprocket 17 adapted to receive power from the actuator of the coal cutter. 70 This may be accomplished by providing the gear 18 adapted to engage the gear 105 of the coal cutter when the latter is retracted to the rear end of the frame 7 and held there preferably by the engagement of the latch 20 75 and the dog 51. To properly adjust the engagement of the gear 18 with the gear 105, I prefer to provide longitudinal fine adjusting means typified by the fork-held set screws 21. To absolutely prevent lateral swaying 80 of the angle iron frame 37, I may provide guides 53 adapted to hold the frame firmly when in retracted position.

The gear 18 is held in a journal on the bracket 22, and through any suitable gearing 85 imparts rotary motion to the shaft 30 on which is a sprocket 31 which through any suitable driving chain 32 imparts power to the sprocket 17 and hence to the wheels 14. If desired, a sprocket 54 on the axle 15 may 90 impart power to a sprocket 55 on the other axle 56 through a chain 57. Intermediate the gear 18 and the shaft 30 I prefer to utilize drive and brake mechanism 33 which may be controlled by the common handle 34 95 and the shaft 35, the latter preferably including adjusting means as the nuts 36. No feature of novelty or invention in this application is based on the specific gearing employed, hence I have not unnecessarily complicated the drawings or specification with the details thereof.

At the back of the machine I may provide hangers 39 for a reel 40 adapted to hold the wire or hose 41 or other conduit or conductor adapted to supply power to the machine. To provide for keeping the conduit or conductor taut when the machine is running backwards, I may provide a friction roll 42 receiving rotation through gearing in 110 the casing 43. The head 44 of the reel 40 rests against this friction roll when the machine is running backward and when running forward the reel 40 is lifted away from the roll 42 and the conduit or conductor 41 115 is unreeled by the forward movement of the truck.

At any desired place on the frame I may provide an adjustable support, herein shown in the form of jack 45, to steady the machine. The function of this support is to support the forward end of the truck or guiding means when the mining machine receiving frame is advanced on the guiding means, and to elevate this end when it is desired to operate at an angle to the horizontal, or when it is desired to load or unload a mining machine on a bench on which the mining machine can operate under its own power as a bottom cutting machine. It 120 125 130

will also be evident that with this construction it is made possible to adapt a standard bottom cutting machine to cutting substantially beyond the end of the trackway in such manner as to provide ample space for the coal to fall without encumbering the track. By the use of an adjustable support, it is also possible to compensate for any unevenness in the mine floor, a feature of decided importance, especially when the guiding means is extended beyond the end of the track or in any direction over a sloping or uneven bottom, as by simply varying the length of the support in a well known manner it is thus possible to provide a sturdy support without any necessity for laying track or leveling the bottom.

In the illustrative embodiment of my invention shown in the drawings I have located the axles 15 and 56 rather close together so as to facilitate turning sharp curves in the track 46 which may cooperate with the wheels 14 which may be flanged as shown. When the axles are as aforesaid, one end of the frame 7 overhangs a considerable distance. To prevent tipping of the frame when in operation, two of the jacks 45 may be located adjacent the end of the overhanging portion of the frame 7. I may swivel the heads 47 of the jacks 45 to the frame, and provide projections 48 adapted to receive the depending portion of the jacks when not in use.

The overhanging of the frame is of marked advantage in loading and unloading the coal cutter from the turntable 1, as the frame may be tipped so as to lower that end of the frame facilitating the loading or unloading of the coal cutter under its own power by means of the flexible positioning chain 103 and the actuator 104 therefor.

For convenience in attaching the end of the aforesaid chain 103, I may provide at various places on the apparatus suitable chain engaging members as the hooks 49.

The following is a description of the operation of the apparatus in driving an entry, a class of work for which it is peculiarly well adapted.

Referring to Fig. 3, the track 46 is laid in the general direction in which the entry is to be extended and the apparatus is run onto said track with the front end of the frame 7 adjacent the wall to be cut. The jacks 45 are then adjusted and the brake applied to steady the frame 7.

The turntable 2 with the coal cutter thereon is swung into the position shown in Fig. 3 and the tension chain 103 is fastened to the front of the framework 7, as shown. The motor 104 is then started, actuating the cutter chain 102 and pulling on the feeding chain 103, thus gradually pulling the sliding bed 2 and the apparatus mounted on it forward along the frame 7, the cutter chain

meanwhile cutting out the coal as shown in Fig. 4. When the position shown in Fig. 4 is attained the bed 2 is locked to the frame 7, by means of the clamp 12, and the pin 4 is removed to permit rotation of the turntable 1 on the bed 2. The end of the tension chain 103 is unfastened from the frame and fastened as shown in Fig. 4.

The cutter chain 102 and feeding mechanism are again started, with the result that the bed 2 remains stationary while the turntable and coal cutter turn axially by the pull of the feeding mechanism on the chain 103 until the position of the cutter shown in Fig. 5 is reached. The coal will then be undercut as shown in Fig. 5. The cutting and feeding is then stopped while the bed 2 is unclamped from the frame 7 by loosening the clamp 12, the turntable 1 again locked to bed 2 and the chain 103 attached to the frame 7 as shown in Fig. 5. The cutting and feeding mechanism then cooperate to pull the bed 2 and superimposed mechanism back, to the position shown in Fig. 6, completing the remainder of the kerf. While the coal so undercut is being removed from this entry, the apparatus may be moved to another entry or used for long wall cutting or breast cutting while still on the truck, but if it is desired to use the coal cutter on a low cut it may easily be dismounted from the turntable 1 by process heretofore described. After being thus dismounted the coal cutter is ready for work in its other capacities for room and pillar cutting or long wall work, while sliding on the mine bottom.

If desired, I may provide distance pieces adapted to raise the shoe 100 of the coal cutter higher above the turntable 1 so as to vary the height of kerf, but I prefer to accomplish this by blocking up the track 46.

It should be noted that the truck mounted guiding means and the swiveled mining machine receiving frame are especially adapted to the driving of entries and room necks where the entry is of greater height than the vein of coal. Under these conditions, the mining machine unit, which is preferably of the self-propelling type, is moved forward on the guides 9 until the coal seam is reached, which is, in entry work, at the end of the guides, and, in the driving of room necks, at one side of the guides. The mining machine may then make the necessary cuts, i. e. in the material above or below the coal or in the coal vein so that the coal may be removed free of impurities. Further, it will also be clear that when desired, the machine may be unloaded directly onto a "bench" and that, after the coal has been mined for some distance in the manner which is termed "bench cutting," the mining machine may be reloaded onto the truck and the rock or other bench drilled and blasted or otherwise removed so as to advance the entryway.

My improved mining apparatus has all the advantages of a short truck, as it will be noted that due to my improved construction, while the center of gravity of the machine during transport is between the wheels in such a manner as to minimize the danger of tipping, the wheels may be placed closely enough together to facilitate the movement of the truck around the sharp bends encountered in mine tunnels. Further, through the use of a supplemental support it has the advantages of a long truck in that when the apparatus is to be used during a cutting operation in an entryway or room-neck where the track is imperfectly laid or cannot be laid, the weight of the mining machine is distributed over a large area, a large part of the same being directly supported by the mine bottom. The spacing of the jacks from the front wheels and under the long overhanging end of the guiding means also makes it possible to bridge the intervening space between the end of a trackway and the face of an entryway or the end of a bench, an important feature, as it is rarely possible to lay the tracks right up to the face of the entry and sometimes undesirable to do so.

As is clearly shown in Figs. 3, 5, and 6, in my improved construction anchorage means are provided on the truck for attaching the end of the flexible feeding means so that it is not necessary to fasten anchors to the entry walls or face to reciprocate the cutting apparatus on the guides, it only being necessary to provide extraneous anchorage means when it is necessary to swing the cutter bar during the transverse cutting operation, as is shown in Fig. 4.

It will also be evident that certain features of my invention, including the longitudinally movable swiveled machine receiving member with my improved means for supporting and guiding the same or feeding the same or the machine relative thereto or to the trackway, or my improved cooperating truck driving means, may be advantageously embodied in various other types of mounted cutters or embodied in transport trucks for room and pillar or other machines, without departing from the spirit of my invention. These and other advantages of my improved mining apparatus will, however, be apparent to those skilled in the art.

While for the purpose of illustration I have herein shown and described one specific embodiment of the invention, it is to be understood that the same is not limited to the constructional details and parts or their relative arrangement herein specifically indicated, but that extensive deviations may be made from the described embodiment without departing from the spirit of the invention, and that many features herein described in combination may be usefully em-

ployed independently or in other connections than in the relations they occupy in the described type of machine.

Claims:

1. Coal cutting apparatus comprising, in combination, a kerf cutter comprising an elongated cutter bar having thereon orbitally movable cutting elements operative to cut a kerf to admit said bar whether the latter be presented to the coal by movement perpendicular to its length, parallel to its length, or when disposed at an acute angle to the face, feeding mechanism, a common actuating motor for both said kerf cutter and said feeding mechanism, rotatable supporting means supporting said kerf cutting element and said actuating motor, a wheel mounted truck, guiding means mounted on said truck and extending longitudinally thereof and adapted to be placed with its forward extremity adjacent the face of the coal and in a position at right angles to the face, and a support for said rotatable supporting means mounted for guided longitudinal movement on said truck mounted guiding means, whereby said kerf cutter may be swung or moved longitudinally to cut a kerf across the end of said guiding means while guided by said guiding means for cutting movement in a single plane, said truck being held stationary during the cutting operation. 95

2. Coal cutting apparatus comprising, in combination, a kerf cutter comprising an elongated cutter bar having thereon orbitally movable cutting elements operative to cut a kerf to admit the bar whether the latter be presented to the coal by movement perpendicular to its length, parallel to its length, or when disposed at an acute angle to the face, a rotatable feeding member, actuating means including a common actuator motor for said kerf cutter and said feeding member; rotatable supporting means supporting said kerf cutting element, said feeding member and said actuator motor; a wheel mounted truck; guiding means mounted on said truck; a support for said rotatable supporting means mounted for guided longitudinal movement in said guiding means; anchorage means; and flexible means connecting said anchorage means and said feeding member, whereby said feeding member by tensioning said flexible means may feed said rotatable supporting means longitudinally on said guiding means and rotate said kerf cutter to make sumping, transverse and withdrawal cuts. 115

3. Coal cutting apparatus comprising, in combination, a kerf cutter comprising an elongated cutter bar having thereon orbitally movable cutting elements operative to cut a kerf to admit the bar whether the latter be presented to the coal by movement perpendicular to its length, parallel to its length, or when disposed at an acute angle to the 125

face, a rotatable feeding member, actuating means including a common actuator motor for said kerf cutter and said feeding member; rotatable supporting means supporting said kerf cutting element, said feeding member and said actuator motor; a wheel mounted truck; guiding means mounted on said truck; a support for said rotatable supporting means mounted for guided longitudinal movement in said guiding means; anchorage means; and flexible means connecting said anchorage means and said feeding member, whereby said feeding member by tensioning said flexible means may swing said rotatable supporting means or may feed said rotatable supporting means longitudinally on said guiding means to make stumping, transverse and withdrawal cuts.

4. Coal cutting apparatus comprising, in combination, a rotatable turntable, a separable chain cutter coal machine of the sliding bed, chain positioned type, mounted on said turntable, locking means for securing said coal machine to said turntable, turntable supporting means including a non-rotatable turntable base, a frame having running gear adapted to support said frame for movement about a mine, said frame being adapted to constitute transport means for said turntable, coal cutting machine, and turntable base, and feeding mechanism to produce relative movement of said turntable base and said frame.

5. Coal cutting apparatus comprising, in combination, a rotatable turntable, a separable chain cutter coal machine of the sliding bed, chain positioned type, mounted on said turntable, locking means for securing said coal machine to said turntable, turntable supporting means including a non-rotatable base, a frame, and feeding mechanism to produce relative movement of said turntable base and said frame, wheels supporting said frame, transmission mechanism for transmitting power to said wheels from the actuator of said coal machine, and locking and positioning means for positioning longitudinally and also angularly about its axis said turntable and said coal machine in proper relation to said transmission mechanism.

6. A turret mounted coal mining machine having a turret and a truck in combination with feeding means adapted to move said turret relative to said truck successively longitudinally, angularly, and longitudinally in the opposite direction, said feeding means including a plurality of anchors disposed in front of said turret and at the side and rear thereof, a rotatable member mounted on said turret, and flexible tension means connectible successively with said anchors and constantly engaging said rotatable member, the cooperation of said rotatable member, said flexible tension means and said anchors be-

ing operative per se to effect the opposite longitudinal movements or the angular movement of said turret.

7. Coal cutting apparatus comprising, in combination, a combined transport and guiding frame adapted to constitute a transport element during movement from place to place in a mine and a guiding frame during certain cutting operations, a rotatably movable support mounted on said guiding frame, a complete coal cutter comprising a shoe on which said cutter is adapted to slide while cutting independently of said guiding frame, a cutter chain, feeding mechanism, and an actuator for said cutter chain and said feeding mechanism; said coal cutter being separably mounted on said support and detachable therefrom for operation independent of said guiding frame.

8. Coal cutting apparatus comprising, in combination, a combined transport and guiding frame adapted to constitute a transport element during movement from place to place in a mine and a guiding frame during certain cutting operations, a rectilinearly and rotatably movable support mounted for movement as a whole on said frame, a complete coal cutter comprising a shoe on which said cutter is adapted to slide while cutting independently of said frame, a cutter chain, feeding mechanism, and an actuator for said cutter chain and said feeding mechanism; said coal cutter being separably mounted on said support and detachable therefrom for operation independent of said frame.

9. Coal cutting apparatus comprising, in combination, a combined transport and guiding frame adapted to constitute a transport element during movement from place to place in a mine and a guiding frame during certain cutting operations, a rotatably movable support mounted on said guiding frame; a complete coal cutter comprising a shoe on which said cutter is adapted to slide while cutting independently of said guiding frame, a cutter chain, flexible tension feeding mechanism, and an actuator for said feeding mechanism; said coal cutter being separably mounted on said support and detachable therefrom for operation independent of said guiding frame.

10. Coal cutting apparatus comprising, in combination, a combined transport and guiding frame adapted to constitute a transport element during movement from place to place in a mine and a guiding frame during certain cutting operations, a rectilinearly and rotatably movable support mounted on said frame, a complete coal cutter on said frame comprising a shoe on which said cutter is adapted to slide while cutting independently of said frame, a cutter chain, flexible tension feeding mechanism, and an actuator for said cutter chain and said feeding mech-

anism; said coal cutter being separably mounted on said support and detachable therefrom for operation independent of said frame.

- 5 11. Coal cutting apparatus comprising, in combination, a relatively short wheeled truck; an elongated guiding frame mounted on said truck and overhanging one end of said truck whereby said end may be placed 10 adjacent the face of an entry with the guiding frame substantially at right angles thereto; a longitudinally movable support mounted for guided longitudinal movement in said frame; a turning support mounted on said 15 longitudinally movable support and longitudinally movable therewith, a kerf cutting element and its driving motor mounted on said turning support, and feeding means driven by said driving motor for longitudinally 20 moving and turning said respective supports, said parts being so constructed and arranged that the longitudinally movable support and parts carried thereon may be superposed over the wheels of said truck during 25 transport.

12. Coal cutting apparatus comprising, in combination, a relatively short wheeled truck; an elongated guiding frame mounted on said truck and overhanging one end of said truck; a longitudinally movable support mounted for sliding guided longitudinal movement in said frame; a turning support mounted on said longitudinally movable support and longitudinally movable therewith, a kerf cutting element and its driving motor mounted on said turning support, and feeding means driven by said driving motor for longitudinally moving and turning said respective supports for making sumping, 40 transverse and withdrawal cuts beyond the overhanging end of said guiding frame, said parts being so constructed and arranged that the longitudinally movable support and parts carried thereon may be superposed over the wheels of said truck during transport.

13. Coal cutting apparatus comprising, in combination, a relatively short wheeled truck adapted for movement on a trackway; an elongated guiding frame mounted on said truck and overhanging one end of said truck whereby said end may be placed adjacent the face of an entry with the guiding frame substantially at right angles thereto; a longitudinally movable support mounted for guided longitudinal movement in said frame; a turning support mounted on said longitudinally movable support and longitudinally movable therewith, an endless kerf cutting element and its driving motor mounted on said turning support, and means for preventing tipping movement of the overhanging end of said elongated frame, said parts being so constructed and arranged that the longitudinally movable support and parts

carried thereon may be superposed over the wheels of said truck during transport.

14. In a mining apparatus, a supporting member presenting longitudinally disposed guiding means extending to a point adjacent the coal face, anchorage means mounted on said supporting member, a swivel support movable longitudinally relative to said supporting member and guided by said guiding means, a mining machine support swiveled on said swivel support and movable longitudinally therewith, a mining machine carried by said machine support and having a driving motor and a cutter bar provided with cutting elements operative on presentation of the bar to the coal at any angle between perpendicularity and parallelism to its path of bar movement to cut a kerf to receive the bar, and means adapted to be fastened to said anchorage means and driven by said machine for moving said machine support longitudinally.

15. In a mining apparatus, a supporting member presenting longitudinally disposed guiding means extending to a point adjacent the coal face, a supplemental supporting member for the guiding means, anchorage means mounted on said supporting member, a swivel support movable longitudinally relative to said supporting member and guided by said guiding means, a mining machine support swiveled on said swivel support and movable longitudinally therewith, a mining machine carried by said machine support, and having a driving motor and a cutter bar provided with cutting elements operative on presentation of the bar to the coal at any angle between perpendicularity and parallelism to its path of bar movement to cut a kerf to receive the bar, and means adapted to be fastened to said anchorage means and driven by said machine for moving said machine support longitudinally.

16. In a mining apparatus, a supporting member presenting longitudinally disposed guiding means extending to a point adjacent the coal face, anchorage means mounted on said supporting member, a swivel support movable longitudinally relative to said supporting member and guided by said guiding means, a mining machine support swiveled on said swivel support and movable longitudinally therewith, a mining machine carried by said machine support and having a cutter bar provided with cutting elements operative on presentation of the bar to the coal at any angle between perpendicularity and parallelism to its path of bar movement to cut a kerf to receive the bar, and flexible means adapted to be fastened to said anchorage means and driven by said machine for moving said machine support longitudinally.

17. In a mining apparatus, a mining ma-

chine truck presenting longitudinally disposed side rails constituting guiding means projecting a substantial distance in advance of the truck wheels, a swivel support movable relative to said truck and guided by said guiding means, a mining machine support swiveled on said swivel support and movable therewith, a mining machine having an elongated cutter chain carrying cutter bar and a driving motor and carried as a whole by said machine support, said bar being provided with cutting elements arranged to cut a kerf to receive the bar on presentation of the latter to the face either perpendicularly or at a substantial angle to the latter.

18. In a mining apparatus, a mining machine truck presenting elongated longitudinally disposed guiding means, truck wheels disposed adjacent the rear end of said truck, cooperating supporting means disposed beneath the opposite end of said truck, truck driving means carried at the rear end of said truck and connected to said wheels, a swivel support slidable over the portion of said guiding means in front of said wheels, a mining machine swiveled on said swivel support having means cooperating with said truck driving means, means for rigidly connecting said mining machine to said swivel support when at an angle relative to said guiding means, and flexible means operatively connected to said machine and to a point in advance thereof for bodily advancing said swivel support approximately to the front end of said guiding means.

19. In a mining machine, a support presenting longitudinally disposed guiding means extending to a point adjacent the coal face, a swivel support slidable longitudinally of said guiding means substantially to the front end thereof, a complete mining machine swiveled on said slidable support, means whereby said mining machine may be attached to said swivel support or detached therefrom for angular movement relative thereto or for use independently thereof, and flexible feeding means operatively connected to said machine whereby the latter may be propelled longitudinally with said slidable support and swung relative thereto or be propelled when used independently of said support.

20. In a mining apparatus, a mining machine truck presenting elongated longitudinally disposed guiding means, truck wheels disposed adjacent the rear end of said truck, cooperating supporting means disposed beneath the opposite end of said truck, truck driving means carried at the rear end of said truck and connected to said wheels, a swivel support slidable over the portion of said guiding means in front of said wheels, a mining machine swiveled on said swivel sup-

port having means cooperating with said truck driving means, means for rigidly connecting said mining machine to said swivel support when at an angle relative to said guiding means, and flexible means operatively connected to said machine and connectible to a plurality of anchorages for bodily advancing said swivel support approximately to the front end of said guiding means and upon release of said mining machine from said swivel support, thereafter swinging said mining machine bodily about its axis thereon.

21. In a mining apparatus, a mining machine truck presenting elongated longitudinally disposed guiding means, truck wheels disposed adjacent the rear end of said truck, cooperating supporting means disposed beneath the opposite end of said truck, truck driving means carried at the rear end of said truck and connected to said wheels, a swivel support guided by said guiding means and slidable over the portion of the same in front of said wheels, a mining machine swiveled on said swivel support having means cooperating with said truck driving means, flexible feeding means driven by said mining machine and successively connectible at a point in advance of said swivel support, at one side of said guiding means and at a point in rear of said swivel support for successively advancing said mining machine and swivel support bodily on said guiding means substantially to the front end thereof, thereafter turning said mining machine transversely about its axis, and subsequently bodily retracting said mining machine and swivel support on said guiding means, and means for rigidly connecting said mining machine to said swivel support during said longitudinal movements.

22. Mining apparatus comprising wheeled guiding means, mining machine receiving means adapted to receive and wholly support a mining machine adjustably mounted on said guiding means for movement longitudinally and angularly relative to said guiding means, and wheel driving means adapted to be driven from a mining machine on said receiving means in a predetermined position of the latter.

23. Mining apparatus comprising wheeled guiding means, mining machine receiving means adjustably mounted for longitudinal and angular movement thereon and relative thereto, and a mining machine of the self-propelling separately operable type carried by said receiving means.

24. Mining apparatus comprising wheeled guiding means, mining machine receiving means adapted slidably to receive a mining machine and mounted for longitudinal sliding movement on said guiding means and for angular movement relative thereto, and

- a self-propelled mining machine slidable on said receiving means and movable therewith.
25. Mining apparatus comprising wheeled guiding means, mining machine receiving means adjustably mounted for longitudinal and angular movement thereon and relative thereto, wheel propelling mechanism, and a mining machine wholly supported by and slidable on and movable with said receiving means and operatively connectible to said wheel propelling mechanism.
26. Mining apparatus comprising wheeled guiding means, mining machine receiving means adjustably mounted for longitudinal and angular movement thereon and relative thereto, wheel propelling mechanism, a mining machine carried wholly by said receiving means and driving said propelling mechanism, and means actuated by said machine for moving the latter longitudinally and angularly relative to said guiding and wheel propelling means.
27. In a mining apparatus, a wheeled truck, a swiveled machine receiving member movable translatively relative thereto, a self-propelled mining machine supported on and movable relative to said receiving member, and means for selectively moving said mining machine or said receiving member relative to said truck.
28. In a mining apparatus, a wheeled truck movable on a trackway, a swiveled machine receiving member slidable bodily longitudinally thereof, a self-propelled mining machine slidably supported on said receiving member, and means for selectively moving said mining machine or said receiving member relative to said trackway.
29. In a mining apparatus, a wheeled truck, a swiveled machine receiving member movable translatively as a whole relative to said truck, a self-propelled separately operable mining machine carried on said receiving member with its center of gravity substantially over the swivel thereof, and means for moving said receiving member relative to said truck.
30. In a mining apparatus, a wheeled truck movable over a trackway, a swiveled machine receiving member movable translatively as a whole relative to said truck, a self-propelled separately operable mining machine carried on said receiving member with its center of gravity substantially over the swivel thereof, and means for moving said receiving member angularly or bodily relative to said trackway.
31. In a mining apparatus, a wheeled truck, a swiveled machine receiving and guiding frame slidable bodily longitudinally of said truck, a self-propelled mining machine carried wholly on said receiving member, and means for moving said swiveled receiving member longitudinally in one direction and angularly relative to said truck and thereafter longitudinally in an opposite direction.
32. In a mining apparatus, a wheeled guiding truck movable on a trackway, wheel driving mechanism thereon, a swiveled machine receiving member slidable bodily longitudinally of said truck, a self-propelled mining machine supported wholly on said member and in one position thereof operatively connectible with said driving mechanism, and means for moving said member to disconnect said driving mechanism and selectively angularly and longitudinally relative to said trackway.
33. Mining apparatus comprising a truck having a long guiding means and a relatively short wheel base, said truck being movable on a mine trackway to the end thereof with the front end of the guiding means extending beyond the trackway, and a sliding pivotal support on said guiding means adapted removably to receive a mining machine of the self-propelling separately operable type.
34. Mining apparatus comprising a truck having a long guiding means and a relatively short wheel base, said truck being movable on a mine trackway to the end thereof with the front end of the guiding means extending beyond the trackway, a separately operable mining machine comprising a cutter bar movable substantially the length of the guiding means, a pivotal mounting for supporting the cutter bar with its free end at one side of the guiding means, and means for moving said cutter bar rectilinearly on the guiding means while so disposed toward an entry face to make a sumping cut therein in advance of said guiding means.
35. Mining apparatus comprising a self-propelling, separately operable mining machine and supporting means therefor comprising a truck having a long guiding means and a relatively short wheel base, said truck being movable on a mine trackway to the end thereof with the front end of the guiding means extending beyond the trackway, and means carried by the guiding means for supporting a mining machine for longitudinal movement in opposite directions relative to the truck, and means for moving said mining machine in both directions for cutting kerfs during said longitudinal movements.
36. Mining apparatus comprising a self-propelling separately operable mining machine and supporting means therefor comprising a truck having a long guiding means and a relatively short wheel base, said truck being movable on a mine trackway to the end thereof with the front end of the guiding means extending beyond the trackway, and means carried by the guiding means for supporting a mining machine for longitudinal movement in opposite directions and an

gular movement relative to the truck, and means for moving said machine longitudinally and angularly for cutting kerfs during said longitudinal and angular movements.

5 37. Mining apparatus comprising a truck having a long guiding means and a relatively short wheel base, said truck being movable on a mine trackway to the end thereof with the front end of the guiding means 70 extending beyond the trackway, bracing means for the front end of the guiding means, and a sliding pivotal support on said guiding means adapted to receive a mining machine of the self-propelling separately 75 operable type.

20 38. Mining apparatus comprising a truck having a long guiding means and a relatively short wheel base, said truck being movable on a mine trackway to the end thereof with the front end of the guiding means extending beyond the trackway, and a sliding pivotal support on said guiding means adapted to receive a mining machine of the self-propelling separately operable type when said sliding pivotal support is adjacent the front end of the guiding means and at an angle thereto.

25 39. Mining apparatus comprising a truck having a long guiding means and a relatively short wheel base, said truck being movable on a mine trackway to the end thereof with the front end of the guiding means extending beyond the trackway, bracing means for the front end of the guiding means, and a sliding pivotal support on said guiding means adapted to receive a mining machine of the self-propelling separately operable type when said sliding pivotal support is adjacent the front end of the guiding means and at an angle thereto.

40 40. Mining apparatus comprising a truck having a long guiding means and a relatively short wheel base, said truck being movable on a mine trackway to the end thereof with the front end of the guiding means extending beyond the trackway, adjustable bracing means hingedly secured to the front end of the guiding means, and a sliding pivotal support on said guiding means adapted to receive a mining machine of the self-propelling separately operable type.

45 41. Mining apparatus comprising a truck having a long guiding means and a relatively short wheel base, said truck being movable on a mine trackway to the end thereof with the front end of the guiding means extending beyond the trackway, and a sliding pivotal support on said guiding means adapted to receive a mining machine of the self-propelling separately operable type and support the mining machine for kerf cutting at either side of or across the end of said guiding means.

60 42. Mining apparatus comprising a truck,

guiding means thereon, truck driving mechanism mounted thereon, mining machine receiving means adjustably mounted on said guiding means for movement longitudinally and angularly relative thereto, a mining machine comprising a driving motor and a kerf cutting element both on said receiving means, and mechanism whereby said driving motor is connected to said truck driving mechanism when the mining machine is in 75 a predetermined position on the guiding means.

43. Mining apparatus comprising a truck having a long guiding means and a relatively short wheel base, said truck being movable on a mine trackway to the end thereof with the front end of the guiding means extending beyond the trackway, truck driving means carried by the truck, means carried by the guiding means for supporting a mining machine having an actuator motor and a kerf cutting element for longitudinal and angular movement as a whole relative to the truck for cutting kerfs during said longitudinal and angular movements, and mechanism adapted to connect said actuator and said truck driving mechanism when the mining machine is in a predetermined position on the guiding means.

44. In a mining apparatus, the combination of extended parallel bars constituting guiding means, a truck normally supporting said guiding means and located towards one end thereof, normally inoperative means carried by said guiding means for supporting the other end thereof at will, and means, mounted for movement longitudinally of said guiding means, for supporting a mining machine of the separately operable type which is operable to cut a kerf when sliding on the mine bottom.

45. In a mining apparatus, the combination of extended parallel bars constituting guiding means, a truck normally supporting said guiding means and located towards one end thereof, normally inoperative means carried by said guiding means for supporting the other end thereof at will, and means including a turntable mounted for movement longitudinally of said guiding means for supporting a mining machine of the separately operable type which is operable to cut a kerf when sliding on the mine bottom.

46. Mining apparatus comprising a truck having a long guiding means and a relatively short wheeled supporting means therefor, a supplemental supporting means for said guiding means, and a sliding pivotal support on said guiding means adapted to receive a mining machine of the self-propelling separately operable type.

47. In a mining apparatus, the combination of extended parallel bars constituting

guiding means, a truck normally supporting said guiding means and located towards one end thereof, normally inoperative means carried by said guiding means for supporting 5 the other end thereof at will comprising extensible props adapted to be moved into substantially upright position beneath said guiding means, and means mounted for movement, longitudinally of said guiding 10 means for supporting a mining machine of the self-propelled separately operable type.

48. Mining apparatus comprising, in combination, a relatively short wheeled truck 15 adapted for movement on a trackway; an elongated guiding frame mounted on said truck and overhanging one end of said truck whereby said end may be placed adjacent the face of the coal beyond the end of the 20 trackway with the guiding frame at substantially right angles to the face of the coal; a longitudinally movable support mounted for guided longitudinal movement in said frame; a turning support mounted on said 25 longitudinally movable support and longitudinally movable therewith; and an endless kerf cutting element and its actuator motor mounted on said turning support, said endless kerf cutting element having a guiding 30 element supporting it for orbital movement in a horizontal plane and arranged to cut a kerf to admit said guiding element when said element makes any acute angle to the direction of its path of bodily movement.

35. 49. Mining apparatus comprising, in combination, a relatively short wheeled truck adapted for movement on a trackway; an elongated guiding frame mounted on said truck and overhanging one end of said truck 40 whereby said end may be placed adjacent the face of the coal beyond the end of the trackway with the guiding frame at substantially right angles to the face of the coal; adjustable bracing means for said end; a longitudinally movable support mounted 45 for guided longitudinal movement in said frame; a turning support mounted on said longitudinally movable support and longitudinally movable therewith; and an endless 50 kerf cutting element and its actuator motor mounted on said turning support, said endless kerf cutting element having a guiding element supporting it for orbital movement in a horizontal plane and arranged to cut a 55 kerf to admit said guiding element when said element makes any acute angle in the direction of its path of bodily movement.

60. 50. Mining apparatus comprising, in combination, a relatively short wheeled truck adapted for movement on a trackway; an elongated guiding frame mounted on said truck and overhanging one end of said truck whereby said end may be placed adjacent the face of the coal beyond the end of the 65 trackway with the guiding frame at sub-

stantially right angles to the face of the coal; a longitudinally movable support mounted for guided longitudinal movement in said frame; a turning support mounted on said longitudinally movable support and longitudinally movable therewith; an endless kerf cutting element and its actuator motor mounted on said turning support, said endless kerf cutting element having a guiding element supporting it for orbital movement in a horizontal plane and arranged to cut a kerf to admit said guiding element when said element makes any acute angle to the direction of its path of bodily movement; and means for preventing tipping movement of the overhanging end of said elongated frame.

51. Mining apparatus comprising, in combination, a relatively short, wheeled truck adapted for movement on a trackway; an elongated guiding frame mounted on said truck and overhanging one end of said truck whereby said end may be placed adjacent the face of the coal beyond the end of the trackway with the guiding frame at substantially right angles to the face of the coal; a longitudinally movable support mounted for guided longitudinal movement in said frame; a turning support mounted on said longitudinally movable support and longitudinally movable therewith; an endless kerf cutting element and its actuator motor mounted on said turning support, said endless kerf cutting element having a guiding element supporting it for orbital movement in a horizontal plane and arranged to cut a kerf to admit said guiding element when said element makes any acute angle to the direction of its path of bodily movement.

35. 52. Mining apparatus including a wheeled truck movable over a trackway and having a longitudinal guide thereon, a mining machine of the separately operable bottom cutting type having an elongated cutter chain carrying cutter bar, means whereby said mining machine is swiveled on said truck and adapted to swing freely thereon across the end thereof or to be held in different fixed angular positions relative thereto, and a swivel support movable longitudinally of said guide and adapted to be held in different longitudinal positions thereon.

60. 53. Mining apparatus including a wheeled truck movable over a trackway and having a longitudinal guide thereon, a mining machine of the separately operable bottom cutting type having an elongated cutter chain carrying cutter bar, means whereby said mining machine is swiveled on said truck 65

- and adapted to swing freely thereon across the end thereof or to be held in different fixed angular positions relative thereto, a swivel support movable longitudinally of said guide and adapted to be held in different longitudinal positions thereon, and operative connections to said mining machine whereby the latter may be swung or moved bodily with said swivel support as desired.
57. Mining apparatus including a wheeled truck movable over a trackway and having a longitudinal guide thereon, a mining machine of the bottom cutting type having flexible feeding means and an elongated cutter chain carrying cutter bar, means whereby said mining machine is swiveled on said truck and adapted to swing freely thereon across the end thereof, to be held in different fixed angular positions relative thereto, or to be removed therefrom for independent operation on a mine bottom, and a swivel support movable longitudinally of said guide and adapted to be held in different longitudinal positions thereon. 70
58. Mining apparatus including a wheeled truck movable over a trackway and having a longitudinal guide thereon, a mining machine of the bottom cutting type having flexible feeding means and an elongated cutter chain carrying cutter bar, means whereby said mining machine is swiveled on said truck and adapted to swing freely thereon across the end thereof, to be held in different fixed angular positions relative thereto, or to be removed therefrom for independent operation on a mine bottom, a swivel support movable longitudinally of said guide and adapted to be held in different longitudinal positions thereon, and operative connections to said mining machine whereby through the use of said flexible feeding means said mining machine may be swung, moved bodily with said swivel longitudinally of said truck, or removed from the latter, as desired. 80
59. Mining apparatus including a wheeled truck movable over a trackway and having a longitudinal guide thereon, a mining machine of the separately operable bottom cutting type having an elongated cutter chain carrying cutter bar, means whereby said mining machine is swiveled on said truck and adapted to swing freely thereon across the end thereof or to be held in different fixed angular positions relative thereto, a swivel support slidable longitudinally of said guide and adapted to be held in different longitudinal positions thereon, and operative connections connectible at will to said mining machine to drive the truck wheels. 100
60. Mining apparatus including a wheeled truck movable over a trackway and having a longitudinal guide thereon, a mining machine of the separately operable bottom cutting type having an elongated cutter chain carrying cutter bar, means whereby said mining machine is swiveled on said truck and adapted to swing freely thereon across the end thereof or to be held in different fixed angular positions relative thereto, a swivel support slidable longitudinally of said guide and adapted to be held in different longitudinal positions thereon, and operative connections connectible at will to said mining machine to drive the truck wheels in one 120
61. Mining apparatus including a wheeled truck movable over a trackway and having a longitudinal guide thereon, a mining machine of the bottom cutting type having flexible feeding means and an elongated cutter chain carrying cutter bar, means whereby said mining machine is swiveled on said truck and adapted to swing freely thereon across the end thereof or to be held in different fixed angular positions relative thereto, a swivel support slidable longitudinally of said guide and adapted to be held in different longitudinal positions thereon, and operative connections connectible at will to said mining machine to drive the truck wheels in one 130
62. Mining apparatus including a wheeled truck movable over a trackway and having a longitudinal guide thereon, a mining machine of the bottom cutting type having flexible feeding means and an elongated cutter chain carrying cutter bar, means whereby said mining machine is swiveled on said truck and adapted to swing freely thereon across the end thereof or to be held in different fixed angular positions relative thereto, a swivel support slidable longitudinally of said guide and adapted to be held in different longitudinal positions thereon, and operative connections connectible at will to said mining machine to drive the truck wheels in one 125

longitudinal position of said machine and swivel.

61. Mining apparatus including a wheeled truck movable over a trackway having a longitudinal guide supported thereon projecting a substantial distance in advance of the truck wheels and supplemental means for supporting said guide in front of the truck wheels, a mining mechanism having an elongated cutter chain carrying cutter bar and of the separately operable type adapted to cut when sliding directly on the mine bottom, and means whereby said bar may be horizontally swiveled on the projecting end of said guide after a longitudinal movement relative to said guide.

62. Mining apparatus including a wheeled truck movable over a trackway having a longitudinal guide supported thereon projecting a substantial distance in advance of the truck wheels and supplemental means for supporting said guide in front of the truck wheels, a mining mechanism having an elongated cutter chain carrying cutter bar and of the separately operable type adapted to cut when sliding directly on the mine bottom, means whereby said bar may be horizontally swiveled on the projecting end of said guide after a longitudinal movement relative to said guide, and operative connections to said mining mechanism whereby the latter may be moved bodily relative to said guide or may be swung thereon as desired.

63. Mining apparatus including a wheeled truck movable over a trackway and having a longitudinal guide supported thereon projecting a substantial distance in advance of the truck wheels and supplemental means for supporting said guide in front of the truck wheels, a mining mechanism having an elongated cutter chain carrying cutter bar and of the separately operable type adapted to cut when sliding directly on the mine bottom, means whereby said bar is horizontally swiveled on said truck and adapted to swing freely thereon, and a swivel carrying member movable longitudinally of said guide.

64. Mining apparatus including a wheeled truck movable over a trackway and having a longitudinal guide supported thereon projecting a substantial distance in advance of the truck wheels and supplemental means for supporting said guide in front of the truck wheels, a mining mechanism having flexible feeding means and an elongated cutter chain carrying cutter bar and of the separately operable type adapted to cut when sliding directly on the mine bottom, means whereby said bar is horizontally swiveled on said truck and adapted to swing freely thereon, a swivel carrying member movable longitudinally of said guide, and means whereby through the use of said flexible feeding means said mechanism may be

moved bodily longitudinally of said guide or swung relative thereto as desired.

65. Mining apparatus including a wheeled truck movable over a trackway and having a longitudinal guide supported thereon projecting a substantial distance in advance of the truck wheels and supplemental means for supporting said guide on the mine bottom, a mining machine of the separately operable bottom cutting type thereon having flexible feeding means and an elongated cutter chain carrying cutter bar, means whereby said mining machine is swiveled on said truck and adapted to swing freely thereon, a swivel carrying member movable longitudinally of said guide, and operative connections whereby through the use of said flexible feeding means said mining machine may be moved bodily longitudinally of said guide or swung relative thereto as desired.

66. Mining apparatus including a wheeled truck movable over a trackway and having a longitudinal guide supported thereon projecting a substantial distance in advance of the truck wheels and supplemental means for supporting said guide in front of the truck wheels, a mining machine of the bottom cutting type having flexible feeding means and an elongated cutter chain carrying cutter bar, means whereby said mining machine may be swiveled on said truck and adapted to swing freely thereon, a swivel carrying member slideable longitudinally of said guide, and operative connections connectible at will to said mining machine to drive the truck wheels.

67. Mining apparatus including a wheeled truck movable over a trackway and having means operating to form an elongated guide, a mining machine of the separately operable bottom cutting type having an elongated cutter chain carrying cutter bar, a swivel movable longitudinally of said guide, and a machine carrying member movable with said swivel and about the latter in which said mining machine is operatively disposed during cutting.

68. Mining apparatus including a wheeled truck movable over a trackway, means thereon cooperating to form an elongated guide, a mining machine of the separately operable bottom cutting type having an elongated cutter chain carrying cutter bar, a swivel movable longitudinally of said guide, a machine carrying member movable with said swivel and about the latter in which said mining machine is operatively disposed during cutting, and means whereby said machine may be moved about said swivel or bodily therewith or relative thereto.

69. Mining apparatus including a wheeled truck movable over a trackway and having a guide thereon, a mining machine of the type which is adapted and normally operative to cut when sliding on its bottom over

- 70 a mine bottom and which is provided with an elongated cutter chain carrying cutter bar, means whereby said mining machine is swiveled on said truck and adapted to swing 5 freely thereon or to be held in different fixed positions relative thereto, a swivel support slideable longitudinally of said guide, and means for fixing said swivel support to said guide in different longitudinal positions.
- 75 10. Mining apparatus including a wheeled truck movable over a trackway and having a guide thereon, a mining machine of the separately operable bottom cutting type having an elongated cutter chain carrying cutter bar, means whereby said mining machine is swiveled on said truck and adapted to swing 15 freely thereon or to be held in different fixed positions relative thereto, a swivel support slideable longitudinally of said guide, and 20 means for fixing said swivel support to said guide in longitudinally different positions relative to the latter comprising a plurality of clamps.
- 80 11. In a mining apparatus, a wheeled truck having a guide thereon, a swivel carrying member slideable relative to said guide, a swivel on said support, a machine carrying member movable bodily with said swivel and about the axis of the latter adapted to receive 85 a mining machine, and means for holding both of said carrying members in position, comprising clamping mechanism and pin mechanism.
- 90 12. In a mining apparatus, a wheeled truck having a guide thereon, a swivel support slideable relative to said guide, a swivel on said support, a machine carrying member movable bodily with said swivel and about the axis of the latter, a flexibly fed 95 mining machine removably attached to said carrying member and movable at will longitudinally thereof, and truck wheel driving mechanism connectible to said machine when all of the above mentioned elements occupy 100 a predetermined position relative to the truck.
- 105 13. In a mining apparatus, a wheeled truck having a guiding surface thereon, a swivel support slideable relative to said surface, a swivel on said support, a machine receiving member movable bodily with said swivel and about the axis of the latter, a separately operable mining machine removably carried by said receiving member, and means 110 for connecting said mining machine to said receiving member, said receiving member to said swivel support, and said swivel support to said truck.
- 115 14. In a mining apparatus, a wheeled truck having a machine receiving member thereon, a mining machine of the flexibly fed bottom cutting type carried on said receiving member and removable at will for work independent thereof, a support slideable on 120 said truck and carrying a swivel for said 125 receiving member, means for holding said elements in different relations, and means whereby said elements may be adjusted through use of the flexible feeding mechanism of said machine.
- 130 75. In a mining apparatus, a wheeled truck having a machine receiving member thereon, a mining machine of the flexibly fed bottom cutting type carried on said receiving member and removable at will for work independent thereof, a support slideable on 75 said truck and carrying a swivel for said receiving member, means for holding said elements in different relations, means whereby said elements may be adjusted 80 through use of the flexible feeding mechanism of said machine, and truck wheel driving mechanism operatively connectible to said machine when said elements assume a predetermined relationship.
- 85 76. Mining apparatus including a guide disposed perpendicularly to a face, a mining machine of the separately operable bottom cutting type thereon having an elongated cutter chain carrying cutter bar, means whereby said bar is supportable on said guide with its cutting extremity free to swing across the front end of said guide about a fixed pivot located in rear of the front end of said guide or held against 90 swinging with said bar at acute angles to said guide and on opposite sides of the latter, means whereby during cutting said bar may be swung by power about said pivot, and power driven means wholly carried on 95 said guide and automatically operated when once connected to feed in a given direction, including connections for feeding said bar and said pivot, when the former is in opposite acute angled positions, at a predetermined rate of feed adapted to cutting whereby during cutting said bar may be moved bodily longitudinally of said guide in opposite directions while said cutter chain rotates in one direction.
- 100 105 110 77. Mining apparatus including a guide disposed perpendicular to a face, a mining machine of the separately operable bottom cutting type thereon having an elongated cutter chain carrying cutter bar, means whereby said bar is supportable on said guide with its cutting extremity free to swing across the front end of said guide about a fixed pivot located in rear of the front end of said guide or held against 115 swinging with said bar at acute angles to said guide and on opposite sides of the latter, means whereby during cutting said bar may be swung by power about said pivot, and power driven means, wholly carried on said guide and automatically operated when once connected to feed in a given direction, including connections for feeding said bar and said pivot when the former is in opposite acute angled positions, at a predetermined 120 125 130 rate of feed adapted to cutting whereby during cutting said bar may be moved bodily longitudinally of said guide in opposite directions while said cutter chain rotates in one direction.

rate of feed adapted to cutting whereby during cutting said bar may be moved bodily longitudinally of said guide in opposite directions while said cutter chain rotates in one direction, and also including supplemental connections for moving said machine bodily longitudinally of said guide at a substantially higher transport speed.

78. Mining apparatus including a wheeled truck movable over a trackway, a mining machine of the separately operable bottom cutting type thereon having an elongated cutter chain carrying cutter bar, means whereby said bar is supportable on said truck with its cutting extremity free to swing across the front end of said truck about a fixed pivot in rear of the front end of the truck or held against swinging with said bar at acute angles to the trackway and on opposite sides of the latter, means whereby during cutting said bar may be swung by power about said pivot, power driven means, wholly carried on said truck and automatically operative when once connected to feed in a given direction, including connections for feeding said bar and said pivot when the former is in opposite acute angled positions, at a predetermined rate of feed adapted to cutting whereby during cutting said bar may be moved bodily longitudinally of the trackway in opposite directions while said cutter chain rotates in one direction.

79. Mining apparatus including a wheeled truck movable over a trackway, a mining machine of the separately operable bottom cutting type thereon having an elongated cutter chain carrying cutter bar, means whereby said bar is supportable on said truck with its cutting extremity free to swing across the front end of said truck about a fixed pivot in rear of the front end of the truck or held against swinging with said bar at acute angles to the trackway and on opposite sides of the latter, means whereby during cutting said bar may be swung by power about said pivot, and power driven means, wholly carried on said truck and automatically operative when once connected to feed in a given direction, including connections for feeding said bar and said pivot when the former is in opposite acute angled positions, at a predetermined rate of feed adapted to cutting whereby during cutting said bar may be moved bodily longitudinally of the trackway in opposite directions while said cutter chain rotates in one direction, and also including supplemental connections for moving said truck bodily longitudinally of a trackway at a substantially higher transport speed.

80. Mining apparatus including a wheeled truck movable over a trackway, a mining machine of the separately operable bottom cutting type thereon having a motor and an elongated cutter chain carrying cutter bar

driven thereby, means whereby said bar is supportable on said truck with its cutting extremity free to swing across the front end of said truck about a fixed pivot or held against swinging with said bar at acute angles to a trackway and on opposite sides of the latter, means driven by the same motor whereby during cutting said bar may be swung by power about said pivot, and power driven means driven by the same motor and wholly carried on said truck and automatically operative when once connected to feed in a given direction, including connections for feeding said bar and said pivot when the former is in opposite acute angled positions, at a predetermined rate of feed adapted to cutting whereby during cutting said bar may be moved bodily longitudinally of the trackway in opposite directions while said cutter chain rotates in one direction.

81. Mining apparatus including a wheeled truck movable over a trackway, a mining machine of the separately operable bottom cutting type thereon having a motor and an elongated cutter chain carrying cutter bar driven thereby, means whereby said bar is supportable on said truck with its cutting extremity free to swing across the front end of said truck about a fixed pivot or held against swinging with said bar at acute angles to a trackway and on opposite sides of the latter, means driven by the same motor whereby during cutting said bar may be swung by power about said pivot, and power driven means driven by the same motor and wholly carried on said truck and automatically operative when once connected to feed in a given direction, including connections for feeding said bar and said pivot when the former is in opposite acute angled positions, at a predetermined rate of feed adapted to cutting whereby during cutting said bar may be moved bodily longitudinally of the trackway in opposite directions while said cutter chain rotates in one direction, and also including supplemental connections for moving said truck bodily longitudinally of a trackway at a substantially higher transport speed.

82. Mining apparatus including a wheeled truck movable over a trackway, a mining machine of the separately operable bottom cutting type thereon having an elongated cutter chain carrying cutter bar, means whereby said bar is supportable on said truck with its cutting extremity free to swing across the front end of said truck about a fixed pivot or held against swinging with said bar at acute angles to a trackway and on opposite sides of the latter, means driven by the same motor and wholly carried on said truck and automatically operative when once connected to feed in a given direction, including connections for feeding said bar and said pivot when the former is in opposite acute angled positions, at a predetermined rate of feed adapted to cutting whereby during cutting said bar may be moved bodily longitudinally of the trackway in opposite directions while said cutter chain rotates in one direction, and also including supplemental connections for moving said truck bodily longitudinally of a trackway at a substantially higher transport speed.

nected to feed in a given direction, including connections for feeding said bar and said pivot when the former is in opposite acute angled positions, at a predetermined rate of feed adapted to cutting whereby during cutting said bar may be moved bodily longitudinally of the trackway in opposite directions while said cutter chain rotates in one direction, and truck wheel driving mechanism operatively connectible at will to said mining machine to propel said truck longitudinally of a trackway at a substantially higher transport speed.

83. Mining apparatus including a wheeled truck movable over a trackway, a mining machine of the separately operable bottom cutting type thereon having a motor and an elongated cutter chain carrying cutter bar driven thereby, means whereby said bar is supportable on said truck with its cutting extremity free to swing across the front end of said truck about a fixed pivot or held against swinging with said bar at acute angles to a trackway and on opposite sides of the latter, means driven by the same motor whereby during cutting said bar may be swung by power about said pivot, power driven means driven by the same motor, wholly carried on said truck and automatically operative when once connected to feed in a given direction, including connections for feeding said bar and said pivot when the former is in opposite acute angled positions, at a predetermined rate of feed adapted to cutting whereby during cutting said bar may be moved bodily longitudinally of the trackway in opposite directions while said cutter chain rotates in one direction, and truck wheel driving mechanism operatively connectible at will to said motor to propel said truck longitudinally of a trackway at a substantially higher transport speed.

84. Coal cutting apparatus comprising, in combination, a rotatable turntable, a separable chain cutter coal machine of the sliding bed, chain positioned type, mounted on said turntable, locking means for securing said coal machine to said turntable, turntable supporting means including a non-rotatable turntable base, a portable guiding frame adapted to constitute transport means for said mechanism during movement about a mine, and feeding mechanism to produce relative movement of the turntable base and frame.

85. Coal cutting apparatus comprising, in combination, a rotatable turntable, a separable chain cutter coal machine of the sliding bed, chain positioned type, mounted on said turntable, locking means for securing said coal machine to said turntable, turntable supporting means including a non-rotatable turntable base, a frame directly receiving said base, and feeding mechanism to produce

relative movement of the turntable base and frame.

86. Coal cutting apparatus comprising, in combination, a rotatable turntable, a separable chain cutter coal machine of the sliding bed, chain positioned type, mounted on said turntable, locking means for securing said coal machine to said turntable, turntable supporting means including a non-rotatable turntable base, a frame, and feeding mechanism to produce relative movement of said turntable base and said frame, the chain cutter of said coal machine being disposed in horizontal planes closely adjacent said frame.

87. In a mining apparatus, a supporting member presenting longitudinally disposed guiding means extending to a point adjacent the coal face, anchorage means mounted on said supporting member, a swivel support movable longitudinally relative to said supporting member and guided by said guiding means, a mining machine support swiveled on said swivel support and movable longitudinally therewith, a mining machine carried by said machine support, said machine being of the type which is separately operable when sliding upon its own bottom on a mine bottom to cut a kerf, and means adapted to be fastened to said anchorage means and driven by said machine for moving said machine support longitudinally.

88. In a mining apparatus, a supporting member presenting longitudinally disposed guiding means extending to a point adjacent the coal face, a supplemental supporting member for the guiding means, anchorage means mounted on said supporting member, a swivel support movable longitudinally relative to said supporting member and guided by said guiding means, a mining machine support swiveled on said swivel support and movable longitudinally therewith, a mining machine carried by said machine support, said machine being of the type which is separately operable when sliding upon its own bottom on a mine bottom to cut a kerf, and means adapted to be fastened to said anchorage means and driven by said machine for moving said machine support longitudinally.

89. In a mining apparatus, a supporting member presenting longitudinally disposed guiding means extending to a point adjacent the coal face, anchorage means mounted on said supporting member, a swivel support movable longitudinally relative to said supporting member and guided by said guiding means, a mining machine support swiveled on said swivel support and movable longitudinally therewith, a mining machine carried by said machine support, said machine being of the type which is separately operable when sliding upon its own bottom on a mine bottom to cut a kerf, and flexible means adapted to be fastened to

said anchorage means and driven by said machine for moving said machine support longitudinally.

90. In a mining apparatus, a mining machine truck presenting longitudinally disposed side rails constituting guiding means projecting a substantial distance in advance of the truck wheels, a swivel support movable relative to said truck and guided by said guiding means, a mining machine support swiveled on said swivel support and movable therewith, a mining machine having an elongated cutter chain carrying cutter bar carried by said machine support, said machine being of the type which is separately operable when sliding upon its own bottom on a mine bottom to cut a kerf, means for locking said machine support to said swivel support with said cutter bar disposed at an angle relative to said truck, and flexible means driven by said machine attached at a point in advance of the swivel support and extending along and to the rear end of said machine for advancing said swivel support and machine bodily along said guiding means.

91. Mining apparatus comprising a truck having a long guiding frame of relatively short wheel base, said truck being movable on a mine trackway to the end thereof with the front end of the guiding frame extend-

ing beyond the trackway, truck wheel driving connections carried by said truck and comprising a primary power receiving member, and a sliding pivotal support on 35 said guiding frame adapted to receive a mining machine of the separately operable self-propelled type and positionable on said guiding frame to permit driving by such a machine of said primary power receiving member.

92. Mining apparatus comprising a transport element provided with running gear, supporting means adjustably mounted on said element for movement bodily longitudinally thereof and also angularly relative thereto, driving means for said running gear carried by said element and including a member rotatable on a stationary axis on said transport element, and mechanism supported by said supporting means comprising cutting mechanism, and an actuator motor therefor, feeding means operable by said actuator motor, and means operable by said actuator motor and engageable with said member to drive the latter and so said running gear when said supporting means is in a predetermined position on said element.

In testimony whereof, I have signed my name to this specification.
